(57) **CLAIM**

The ornamental design for a vehicle roof sun visor, as shown and described.

DESCRIPTION

FIG. 1 is a front perspective view of a first embodiment of a vehicle roof sun visor in a position of use, according to our new design;

FIG. 2 is a front perspective view of the vehicle roof sun visor shown in FIG. 1;

FIG. 3 is a top plan view of the vehicle roof sun visor shown in FIG. 1;

FIG. 4 is a bottom plan view of the vehicle roof sun visor shown in FIG. 1;

FIG. 5 is a front elevational view of the vehicle roof sun visor shown in FIG. 1;

FIG. 6 is a left side elevational view of the vehicle roof sun visor shown in FIG. 1;

FIG. 7 is a right side elevational view of the vehicle roof sun visor shown in FIG. 1;

FIG. 8 is a front perspective view of a second embodiment of a vehicle roof sun visor in a position of use;

FIG. 9 is a front perspective view of the vehicle roof sun visor shown in FIG. 8;

FIG. 10 is a top plan view of the vehicle roof sun visor shown in FIG. 8;

FIG. 11 is a bottom plan view of the vehicle roof sun visor shown in FIG. 8;

FIG. 12 is a front elevational view of the vehicle roof sun visor shown in FIG. 8;

FIG. 13 is a left side elevational view of the vehicle roof sun visor shown in FIG. 8; and,

FIG. 14 is a right side elevational view of the vehicle roof sun visor shown in FIG. 8.

The dashed broken lines in the drawings show portions of the vehicle roof sun visor that form no part of the claimed design.

1 Claim, 10 Drawing Sheets
